9 Claims. (Cl. 252—192)

1

The present invention relates to the removal of free sulfur and organic sulphydryls from hydrocarbon mixtures and, more particularly, to the removal of mercaptans from hydrocarbon distillates.

For a number of years it has been the practice of the oil refiner to remove free sulfur and alkyl and aryl sulphydryls, i. e. mercaptans and thiophenols, respectively, from hydrocarbon mixtures. As first practiced, aqueous alkaline solutions were used but it soon became evident that the partition coefficient for the mercaptans of more than two carbon atoms for the system oil-aqueous alkaline solution did not favor practical extraction of the higher molecular weight sulphydryls from the hydrocarbon mixtures. This deficiency later was overcome by adding to the aqueous alkaline solution a substance, generally known in the art as a solutizer, which enhanced the capacity of aqueous alkaline solutions for extracting sulphydryls from hydrocarbon mixtures; or, in other words, an aqueous alkaline solution containing a solutizer has a partition coefficient for sulphydryls in the system oil-aqueous alkaline solution of a solutizer favoring practical extraction of the sulphydryls in the oil by the aqueous alkaline solution. The partition coefficient for sulphydryls in the system oil containing sulphydryls-aqueous alkali metal hydroxide-containing solutizer is known generally in the art as the K_d value. The K_d value is the ratio of the concentration of the sulphydryl in the aqueous phase to the concentration of the sulphydryl in the hydrocarbon phase.

Many compounds have found use to a greater or lesser extent as solutizers. Two compounds in particular have received particular attention, to wit: isobutyric acid and alkyl phenols. Of the two the latter is more commonly used because the alkyl phenols are present in the products of cracking of hydrocarbons, particularly mineral oil. The alkyl phenols are used in an aqueous solution of alkali metal hydroxide; the choice between sodium hydroxide and potassium hydroxide generally being dependent upon economic factors as well as the limit of solubility of the alkyl phenolates. Generally, the aqueous solution of alkali metal hydroxide is 4.0 normal to 6.0 normal to alkali metal hydroxide and 1.0 normal to 3.0 normal to alkali metal alkyl phenolate when using potassium hydroxide and the potassium alkyl phenolates, and 3.0 normal to 5.0 normal to alkali metal hydroxide and 1.0 normal to 2.0 normal to alkali metal alkyl phenolate when using sodium hydroxide.

2

In general, the removal of sulphydryls from hydrocarbon mixtures or from mineral oil distillates comprises contacting the hydrocarbon mixture containing alkyl and/or aryl sulphydryls, i. e. mercaptans and/or thiophenols with an aqueous alkaline solution containing a solutizer. The aqueous solution containing the extracted sulphydryls and solutizer is separated from the hydrocarbon mixture and the fouled solutizer solution regenerated. Regeneration of the fouled aqueous solution may be accomplished in either of two operations. The fouled aqueous solution may be steamed and the sulphydryls thus vaporized or entrained in the steam or the sulphydryls may be oxidized to disulfides with oxygen in the presence of a catalyst such as the sulfides of nickel, iron, etc. as described by Rosenstein in U. S. Patent Number 1,943,744, or in the presence of a soluble phenolic oxidation promoter such as described in the copending applications filed June 11, 1943, in the names of John Happel and Stephen P. Cauley, Serial Nos. 490,490 and 490,491, now U. S. Patent No. 2,516,837. In application Serial Number 490,490 these inventors have disclosed a process wherein gasoline or other light hydrocarbon fraction containing mercaptan sulfur is contacted with a caustic alkali reagent of the type normally used for the removal of mercaptan sulfur and the reagent containing mercaptans is then separated from the treated oil. The reagent containing mercaptans is regenerated by blowing gas containing free oxygen therethrough in the presence of polyhydroxybenzenes, hydroquinone and pyrogallol. In application Serial Number 490,491 the same inventors have disclosed a similar process in which the alkaline reagent containing mercaptans is regenerated by blowing gas containing free oxygen therethrough in the presence of polyhydroxybenzene carboxylic acids and derivatives thereof such as protocatechuic acid, gallic acid, tannic acid and the like and various tannin materials derived from oak-bark, quinine-bark, coffee, moringa-tannin, cutch, chestnut, logwood, sumac and other natural sources of such tannin materials. After regeneration, the aqueous alkaline solution containing the solutizer or solutizers is ready for use in the treatment of further amounts of hydrocarbon mixtures containing sulphydryls.

The treatment of some hydrocarbon distillates, particularly some mineral oil distillates, involves the removal of free sulfur. In the past this has been achieved to the greater or lesser satisfaction of the refiner by contacting the hy-

drocarbon mixture containing the free sulfur with aqueous solutions of alkali metal polysulfides in a manner similar to that employed in extracting sulfhydryls. However, with this difference the polysulfide solution is not readily regenerated.

Thus, when it has been necessary to remove free sulfur as well as sulfhydryls from hydrocarbon it has been necessary to use two separate and distinct extraction media. It has now been discovered that an aqueous alkaline solution of the novel solutizer can be used not only to extract sulfhydryls but also to extract free sulfur from hydrocarbon mixtures.

The novel solutizer is that portion of the by-product tar obtained in the production of thiophene as described in application for United States Letters Patent Serial No. 693,176, filed August 27, 1946, in the names of Rowland C. Hansford, Herbert C. Rasmussen and Alexander N. Sachanen (now U. S. Patent Number 2,450,659), which is soluble in aqueous alkali metal hydroxide solution. As described in this copending application, sulfur and one or more normal C₄ aliphatic hydrocarbons are separately heated to temperatures such that combining the preheated sulfur and preheated hydrocarbon material will give a mixture having a temperature in excess of about 850° F. The preheated reactants are mixed and the temperature of the mixture maintained in excess of about 850° F. for a period of time sufficient to produce the desired products. Thereafter the temperature of the mixture is reduced to less than about 850° F. With the exception of hydrogen sulfide and a tar, thiophene or butadiene are the principal compounds obtained. The novel solutizer is obtained from the aforesaid tar.

One form of the novel solutizer is obtained by extracting the aforesaid by-product tar with 30% aqueous alkali metal hydroxide solution. Another method of obtaining the novel solutizer comprises steam distilling the aforesaid by-product or "thiophene tar" and subjecting the steam distillate to vacuum distillation. The fraction boiling between 107° F. @ an absolute pressure of 10 millimeters of mercury to 127° F. @ an absolute pressure of 10 millimeters of mercury contains the solutizer. This fraction has a major constituent thiophene-3-thiol,

A further method comprises allowing the "thiophene tar" to age and steam distilling the "aged thiophene tar" to obtain a product that is about 90% caustic soluble. It is characteristic of this latter method that the quantity of liquid product is less than that from fresh tar and that the distillate contains less thiophene-3-thiol. On the other hand, the distillate from "aged thiophene tar" is markedly superior to thiophene-3-thiol as a solutizer for sulfhydryls.

Several explanations for this apparent anomaly are possible. One may be suggested without in any way limiting the scope of this invention. It has been determined that a trithiocompound is also present in the "thiophene tar." On the basis of knowledge presently available, the formula

(dithiothiophane or 3,4-thiolanedithione) has been assigned to this trithiocompound. This compound is soluble in aqueous caustic when heated at 100° to 212° F. for some time with aqueous caustic solution containing 20 weight per cent sodium hydroxide. It appears possible that the trithiocompound is enolized by the treatment at elevated temperatures in the aqueous caustic solution to a compound with weakly acidic hydrogen atoms which is a better solutizer than thiophene-3-thiol.

At this time it is to be noted that "aged thiophene tar" is the aforesaid by-product "thiophene tar" which has been allowed to stand at atmospheric conditions for several weeks. A steam distillation of the "thiophene tar" apparently results in some type of steam pyrolysis, for a large amount of thiophene-thiol is obtained on steam distilling a "fresh thiophene tar," i. e. after immediate recovery from the process producing it. However, after allowing the tar to stand at atmospheric conditions for several weeks before steam distillation, the yield is much smaller and the product obtained contains only a small amount of thiophene-thiol.

As was pointed out hereinbefore, a satisfactory means for determining the solutizer value of a compound is to determine the K₄ value of an aqueous solution of the compound for a sulfhydryl dissolved in a hydrocarbon. The K₄ value of three forms of the novel solutizer was determined for normal butyl mercaptan dissolved in isoctane. The K₄ value of two standard solutizer solutions for normal butyl mercaptan was determined under the same conditions. The data thus obtained are given in the appended table.

Solutizer solution I

An aqueous solution 4 normal to potassium hydroxide (KOH) and 2 normal to the steam distillate of "aged thiophene tar" on the basis of a molecular weight of 116 for the solutizing constituents of the tar and that 90 per cent of the distillate is soluble in the aqueous caustic solution.

Solutizer solution III (4N KOH—2N KCr)

An aqueous solution 6 normal to potassium hydroxide (KOH) and 2 normal to potassium alkyl phenolate (potassium salt of metacresol).

Solutizer solution III (4N KOH—2N Kcr)

An aqueous solution 4 normal to potassium hydroxide (KOH) and 2 normal to potassium alkyl phenolate (potassium salt of metacresol).

Solutizer solution IV

An aqueous solution 4 normal to potassium hydroxide (KOH) and 2 normal to the fraction of steam distillate of "fresh thiophene tar" boiling at 127-168° F. at a pressure of 10 millimeters of mercury on the basis of a molecular weight of 130 and that only 42 per cent of the fraction is soluble in the alkaline solution.

Solutizer solution V

An aqueous solution 4 normal to potassium hydroxide (KOH) and 2 normal to thiophene-3-thiol obtained by vacuum distillation of steam distillate of "fresh thiophene tar"; 95 per cent thiophene-3-thiol.

The K₄ values at equilibrium for the solutizer solutions enumerated hereinbefore were obtained by mechanically agitating isoctane containing 75 normal butyl mercaptan in a closed container for

one hour at a treating ratio of 0.1 at room temperature under an atmosphere of nitrogen.

Solutizer solution	Sulfur content of isoctane at equilibrium as weight percent RSH	Approximate volume percent of solutizers	K _a
Control	0.1420	22	145.0
II	0.0092	22	59.0
III	0.0206	22	
IV	0.0092	23	145.0
V	0.0320	26	33.5
	0.0343	23	32.3

These data establish that 6N KOH—2N KCr (II) is superior to 4N KOH—2N KCr (III) as a solutizer. These data also establish that a 4N KOH solution containing sufficient of the steam distillate of "aged thiophene tar" to make the solution 2 normal thereto (I) is equivalent to the 6N KOH—2N KCr (III) and superior to the 4N KOH—2N KCr (III) as a solutizer. These data also establish that solutizer Solutions IV and V are equivalent in solutizing power and, while of approximately one-half the solutizing power of 4N KOH—2N KCr have useful solutizing powers.

The ability of the novel solutizer to extract free sulfur from hydrocarbon solutions of the same is demonstrated by the following.

A 30 weight per cent solution of sodium hydroxide (NaOH) of crude "aged thiophene tar" (approximately 15% by volume including the caustic insoluble material) when agitated for five minutes with an equal volume of isoctane containing 6 parts per million of free sulphur (of the order of free sulfur concentration in petroleum distillates) reduced the free sulfur content of the isoctane to one part per million as shown by the nitroprusside fading time.

It is to be understood, as is generally known to those skilled in the art, that aqueous solutions of sodium hydroxide may be used. Accordingly, the use of aqueous solutions 1.0 normal to 6.0 normal to sodium hydroxide and containing an effective amount of the novel solutizer is within the purview of the present invention. It is also to be understood that the present invention is not limited to thiophene-3-thiol or the trithiocompound described hereinbefore but includes the homologues of thiophene-3-thiol, the trithiocompounds of "fresh or aged thiophene tar" as well as derivatives and polymers of the foregoing and condensation products with other constituents of the thiophene tar or, in general, that portion of "thiophene tar," fresh or aged, which is soluble in an aqueous solution of alkali metal hydroxide containing about 5 weight per cent to about 40 weight per cent of alkali metal hydroxide.

I claim:

1. A method for producing material suitable for use as a solutizer in the removal of sulfhydryls from admixture with hydrocarbons which comprises separately preheating sulfur and a C₄-hydrocarbon selected from the group consisting of normal butane, normal butenes and butadienes, to a temperature such that combining said sulfur and said hydrocarbon will give a reaction mixture having a temperature between 850° F. and about 1400° F.; mixing the preheated sulfur and the preheated hydrocarbon; reacting said preheated sulfur and said preheated hydrocarbon at a reaction temperature varying between 850° F. and about 1400° F. to yield a mixture containing a thiophene tar, immediately reducing the temperature of the mixture containing said tar to a temperature less than 850° F., separating the tar from said mixture, treating said tar to obtain a fraction soluble in aqueous about 5 to about 40 weight per cent alkali metal hydroxide and a fraction insoluble in said aqueous alkali metal hydroxide and separating said soluble fraction from said insoluble fraction.

- 5 2. The method for producing material suitable for use as a solutizer in the removal of sulfhydryls from admixture with hydrocarbons as described and set forth in claim 1 wherein the separated tar is subjected to steam distillation and a fraction of the steam distillate boiling at about 127° to about 168° F. at an absolute pressure of 10 millimeters of mercury is separated.
- 10 3. The method for producing material suitable for use as a solutizer in the removal of sulfhydryls from admixture with hydrocarbons as described and set forth in claim 1 wherein the separated tar is contacted with an aqueous solution containing about 20 to about 30 weight per cent alkali metal hydroxide and a fraction soluble in an aqueous solution containing about 5 to about 40 weight per cent alkali metal hydroxide.
- 15 4. A solution for the extraction of free sulfur and sulfhydryls from hydrocarbon fluids which comprises an aqueous alkaline solution to which has been added a water-insoluble fraction of the steam distillate of thiophene tar in amount effective to increase the capability of said aqueous alkaline solution to dissolve sulfhydryls, said fraction of said steam distillate having a boiling range of about 127° to about 168° F. at an absolute pressure of 10 millimeters of mercury; said thiophene tar having been obtained by separately preheating sulfur and a C₄-hydrocarbon selected from the group consisting of normal butane, normal butenes and butadienes to a temperature such that combining said sulfur and said hydrocarbon will give a reaction mixture having a temperature varying between about 850° F. and about 1400° F., mixing the preheated sulfur and the preheated hydrocarbon, reacting said preheated sulfur and said preheated hydrocarbon at a reaction temperature varying between 850° F. and about 1400° F. to yield a mixture containing a thiophene tar, immediately reducing the temperature of said mixture containing said thiophene tar to a temperature of less than 850° F., and separating said tar from said mixture.
- 20 5. A solution for the extraction of free sulfur and sulfhydryls from hydrocarbon fluids as set forth and described in claim 4, wherein the steam distillate is derived from aged thiophene tar.
- 25 6. A solution for the extraction of free sulfur and sulfhydryls from hydrocarbon fluids as set forth and described in claim 4, wherein the steam distillate is derived from fresh thiophene tar.
- 30 7. A solution for the extraction of free sulfur and sulfhydryls from hydrocarbon fluids which comprises an aqueous alkaline solution to which has been added a fraction of thiophene tar in amount effective to increase the capability of said aqueous alkaline solution to dissolve sulfhydryls, said fraction of thiophene tar being soluble in aqueous solutions containing about 5 to about 40 weight per cent of alkali metal hydroxide, said thiophene tar having been obtained
- 35 40 45 50 55 60 65 70 75

by separately preheating sulfur and a C₄-hydrocarbon selected from the group consisting of normal butane, normal butenes and butadienes to a temperature such that combining said sulfur and said hydrocarbon will give a reaction mixture having a temperature varying between about 850° F. and about 1400° F., mixing the preheated sulfur and the preheated hydrocarbon, reacting said preheated sulfur and said preheated hydrocarbon at a reaction temperature varying between 850° F. and about 1400° F. to yield a mixture containing a thiophene tar, immediately reducing the temperature of said mixture containing said thiophene tar to a temperature of less than 850° F., and separating said tar from said mixture.

8. A solution for the extraction of free sulfur and sulfhydryls from hydrocarbon fluids as set forth and described in claim 7, wherein the fraction of thiophene tar soluble in aqueous solutions containing about 5 to about 40 weight per cent of alkali metal hydroxide is derived from aged thiophene tar.

10

5

9. A solution for the extraction of free sulfur and sulfhydryls from hydrocarbon fluids as set forth and described in claim 7, wherein the fraction of thiophene tar soluble in aqueous solutions containing about 5 to about 40 weight per cent of alkali metal hydroxide is derived from fresh thiophene tar.
